UNITED STATES PATENT OFFICE.

RUDOLF KLIMA AND HANS REISCHENBACHER, OF SALZBURG, AUSTRIA.

SNOWPLOW FOR LOCOMOTIVE OR RAILWAY ENGINES.

Application filed November 13, 1925, Serial No. 68,854, and in Austria November 24, 1924.

This invention relates to improvements in snow-plows for locomotive or railway engines, designated to clear away the snow from the line, as well as also in the stations 5 and adapted to be quickly adjusted or suited to the railway-section or gauge, in order to free of snow the desired width of the line.

The essential feature of the present invention consists in that to snow-plow halves, 10 which are preferably operated by steam and firmly attached to the front side of the engine, are secured shovels, adapted to move round horizontally disposed axle-joints and to the sides of the said snow-plow halves are attached driven wings, adapted to be moved round vertically arranged axles. Preferably 15 these wings can be raised and lowered simultaneously and fixed in the desired position.

20 Several modes of carrying out the present invention are illustrated by way of example on the accompanying sheet of drawings in which:—

Fig. 1 shows in side view the forward end 25 of a railway engine to which is attached a snow-plow according to the present invention.

Fig. 2 illustrates the arrangement shown in Fig. 1 in plan view and sectional plan 30 view.

Fig. 3 illustrates in elevation the attachment of the side-wings.

Fig. 4 shows on an enlarged scale the 35 valve for operating the driving cylinder.

Fig. 5 illustrates in side view the arrangement of the steam-supply pipes, leading from the driver's cabin of an engine to the shovels and wings, which are situated in the lowered position.

40 Fig. 6 shows the front end of an engine with the members of the snow-plow in the inoperative or raised position.

Figs. 7 and 12 illustrate on an enlarged 45 scale two modified constructions for raising the shovel-parts.

Figs. 8 to 11, 13 and 14 are detail views.

In the embodiment shown in Figs. 1 and 2, firm snow-plow halves 2 are attached to the forward end 1 of the engine in such a 50 manner, that they extend forwardly at an incline and diverge from the middle between the rails toward the latter. Shovels 4 are rotatably secured to the snow-plow halves 2 by means of links or joints 3, as shown in Fig. 1, the said shovels being suitably curved.

In order to protect these shovels when running onto the rails or against obstacles, the forward ends of the same are provided with members 5, shaped like sledge-runners and consisting of a material of suitable strength. 60 The shovels 4 rest on wedge-shaped supports 6, which are arranged on the firm snow-plow halves 2, so that the same serve as bearing and take up the pressure. A resisting stiffness is provided by the arrangement of 65 stiffening rails 7, which rest against the cross-frame of the engine.

A steam-drive serves for adjusting the shovels 4. The former comprises four steam-cylinders, arranged in pairs in the space enclosed by the snow-plow halves 2. The steam-cylinders 9 are provided with two compartments, and by means of arms 10, pivoted to the snow-plow halves 2 and with the aid of connecting rods 11, transmit the 70 steam-power to the shovels 4, which, as shown in Fig. 1, can be moved from the position in full lines into the position illustrated in dotted lines, whereby the wings are raised beyond the firm snow-plow section. 80

Wings 12 and 13, forming an extension of the shovels 4 at both sides, are movably secured to the snow-plow halves 2 by means of links or hinges 14 and 15 respectively. The wings 12 and 13 are furnished with 85 curved members 16, the bottom end of which is wedge-shaped (Fig. 3), and rollers 17, which are secured to suitable supports, rest against these wedge-shaped faces, so that the same roll off the roller 17 with the wedge-shaped part of the curved members 16 and are raised or lowered if the wings 12, 13 are turned.

As shown in Fig. 2, the curved members form effective stiffenings of the wings 12, 95 13 and were provided with recesses 18, which are engaged by locking bolts 19 (Fig. 22), in order to secure the wings 12, 13 in the adjusted position. The pressure of the snow acting on the wings is transmitted by the 100 same, by the curved members and by the locking bolts to the frame of the engine. The locking bolts are arranged resiliently and close automatically, whereby the tension can be released from the driver's cabin, for 105 instance by means of a foot-lever, in order to permit the rotation of the wings. Fig. 5 shows the arrangement of such a foot-lever 20, which is operated against the action of a spring 21 and adjusts a connecting rod 110

22, which actuates a locking rod 24 by means of a double-armed lever 23. The wings 12 and 13, as well as the shovels 4, are adjusted by steam-power. In order to obtain this object, two steam-cylinders 25 and 26 are provided which, for instance, are arranged at the front corner of the engine and with the aid of piston-rods 27, hinged to the wings 12 and 13 respectively, move the latter outwardly or inwardly, whereby the wings are simultaneously raised and lowered by the curved members 16 and the fixed rollers 17. In the raised position the wings rest against the cylinder 28 of the engine, so that the same are protected against any obstacle. In the fully lowered position the bottom face (Fig. 3) of the wing extends about one centimetre below the height of the rail, but the lower position-limit of the wings can be regulated according to the wedge-angle of the curved members. According to the gauge, the wings may take up any desired position.

The steam-supply to the cylinders 9 and 25 and 26 respectively is effected through steampipes 30 and 31 respectively by means of a valve, illustrated in Fig. 4. The plug 32 of the valve is furnished with a right-angled passage 33 and an inclined passage 34, which advances with respect to the passage 33, e. g., it is opened in advance during the rotation of the plug and provides at 35 for an outlet in advance. Therefore the inoperative side of the piston is relieved earlier, before the operative side is subjected to pressure. For instance if steam passes through the passages 36 and 37 into the cylinder, the passage 38 on the second side of the cylinder is connected, slightly in advance, with the exhaust conduit 39. The procedure is reversed when reversing the valve. As shown in Fig. 5 the pipes 30 and 31 lead from the driver's cabin of the engine to the change-valves 32 arranged in the same.

In order to facilitate the breaking up of snow, a member 41 provided with a sharp cutter 40 (Fig. 1) is fixed to the front wall 1 of the engine by angle-irons or the like.

According to the embodiments illustrated in Figs. 7 to 14, the shovels 4 can be folded up and down, as well as raised and lowered. The raising and lowering motion of the shovels 4, for instance operated by steam, is the principal movement of the height-adjustment, while further the folding movement of the shovels is rendered possible as auxiliary movement, in order to avoid a damage to the shovels in the event of meeting an obstacle.

Figs. 7 and 12 show two modes of raising and lowering the shovels 4. According to the construction illustrated in Fig. 7, the shovels 4 slide on fixed guide-jaws 44 of the

inside faces, by means of two movable jaws 42 and 43 (Fig. 9) connected by screws. The outer jaw 42 forms at the same time the wedge-support 6, shown in Fig. 1, between the shovel 4 and the fixed snow-plow halves 2 and is provided with an eye 45 for the rotatable attachment of the shovel 4. Thus the latter is pivotally secured to the movable jaw 43, so as to be folded up and down and rests against the wedge-surface of the outer jaws 42. Cylindrical spiral springs 46 pull the shovels 4 toward the wedge-faces 42 and by the same are held against any snow-pressure, which may act from the bottom, while they yield upward in case of shocks of great strength, such as for instance when meeting obstacles with the leading jaws 47 (Fig. 7), and are automatically lowered again after having passed the obstacle.

The inner jaws 43 of each shovel are provided with a rack, and the latter is engaged by a toothed wheel 49, mounted on the driving shaft 48. An arm 50 is secured to the driving shaft 48 and is connected with the piston rod of a steam-cylinder 51, so that on operating the latter the arm 50 is rotated, as shown in Fig. 7, and raises or lowers the racks 43 by means of the toothed-wheels 49. Thereby the shovel 4 moves from the position indicated in dotted lines. The steam-cylinder 51 is operated in similar manner as in the event of the steam-cylinders 9, 25, 26 according to Figs. 4 and 5. Wedges 52 are provided in order to fix the shovels 4 in any convenient height, the former being connected by a pull-rod 53 and are under the influence of a cylindrical spiral spring 54. The pull-rod 53 can be shifted from the driver's cabin of the engine by means of a lever arrangement 55, so that the two wedges 52 can be pushed underneath the racks 43 and according to their position limit the downward movement of the racks 43 according to requirement. The adjustment of the pull-rod 53 can be fixed in convenient manner, for instance by means of locking bolts provided in the driver's cabin (not illustrated). The shovels 4 are furnished with recesses 56 in order to pass underneath the rail-head in their lowest position. In the somewhat raised position of the shovels, for instance when travelling through stations, these recesses 56 may be covered by a plate 58, connected with the pull-rod 53 by means of a link 57. On raising the shovels, these plates 58 are moved automatically to the side.

A hinge-joint 59 of T-shape in cross-section is arranged in the construction shown in Fig. 12. This joint is provided with an extension 60, which enters a groove 61 of the rack-jaw 62, with which it is connected by bolts 63. Both jaws 59 and 62 slide at the outside and inside along the fixed snow-plow halves 2 between the two guide-jaws 64. The shovels 4 are pivotally attached to the

hinge 59 by means of a link 65. All other parts may be constructed and arranged as in the embodiment shown in Fig. 7.

Having thus described our invention, what we claim and desire to secure by Letters Patent is:—

1. Snow-plow for railway engines, comprising snow-plow halves fixed to the forward end of the engine, vertically movable shovels secured to the snow-plow halves and horizontally movable wings attached to the sides of the snow-plow halves.
2. Snow-plow for railway engines as claimed in claim 1, comprising means for raising and lowering the wings, and means for locking the latter in position.
3. Snow-plow for railway engines as claimed in claim 1, comprising steam-cylinders for operating the wings and shovels.
4. Snow-plow for railway engines as claimed in claim 1, comprising racks for raising and lowering and securing in posi-

tion the shovels attached to the fixed snow-plow halves.

5. Snow-plow for railway engines as claimed in claim 1, comprising racks for raising and lowering and securing in position the shovels attached to the fixed snow-plow halves, horizontal pivots secured to the racks round which the shovels may move, and springs for retaining the shovels in position.

6. Snow-plow for railway engines as claimed in claim 1, comprising racks for raising and lowering and securing in position the shovels attached to the fixed snow-plow halves, means for operating the racks, and stops for regulating the lift of the shovels.

In testimony whereof we affix our signatures.

KLIMA RUDOLF.
REISCHENBACHER HANS.
